UNITED STATES PATENT OFFICE.

FRANKLIN B. BECKWITH, OF PLATTSOMOUTH, NEBRASKA.

WASHING-MACHINE.

1,298,645.

Specification of Letters Patent.

Patented Apr. 1, 1919.

Application filed November 11, 1918. Serial No. 262,066.

To all whom it may concern:

Be it known that I, FRANKLIN B. BECKWITH, a citizen of the United States, residing at Plattsmouth, in the county of Cass and State of Nebraska, have invented certain new and useful Improvements in Washing-Machines, of which the following is a specification.

This invention relates to an improvement 10 in washing machines, and has for one of its objects to provide a machine having parts so arranged that the vertical shaft and its dolly may have its required reciprocatory rotation with greater facility than ordinary. 15 Another object is to provide convenient means for a movement of the machine from one part of a room to another, whether the tub is filled or empty. Other objects relate to simplicity in construction so that the 20 parts may be economically constructed and will be durable. The invention includes an axle provided with wheels arranged below the tub, adapted to rotate during operation, as balance-wheels, or may be used as a 25 truck upon which the entire weight of the tub and contents may be supported, both of these features being found to be of great advantage.

With the foregoing objects in view, the 30 invention presents a novel construction, combination and arrangement of parts as described herein and claimed, and as illustrated in the drawings, it being understood that size, form, proportion and minor 35 details may be changed without departing from the invention, the scope of the invention being determined by the appended claims.

In the drawing, Figure 1 is a view in longitudinal section of a washing machine embodying my invention, one of the guides for a segmental arm being also in section. Fig. 2 is a plan view of the machine. Fig. 3 is a side view showing the machine disposed in 45 an inclined position and supported, in part, upon wheels. Fig. 4 is a sectional detail showing the alining gear-wheel splined on the vertical shaft. Fig. 5 is a rear side view of the machine. Fig. 6 shows one of the 50 axle-bearing arms employed. Fig. 7 is a detail showing a locking means for an axle-bearing arm.

I provide a tub 8 of any suitable proportion, the conventional legs and lid therefor 55 being indicated, respectively, at 9 and 10. Agitating devices are employed consisting,

in part, of an alining gear-wheel 11 which, as best shown in Fig. 4, has a downwardly projecting, tubular stem *a* with a terminal annular flange *b*, the aperture *c* for the wheel 60 11 and its stem preferably being angular in cross-section for receiving the vertical spindle or dasher-shaft 12, upon the lower end of the latter being slidably mounted, the conventional, non-rotatable dolly 13, the 65 stem *a* having bearings in the pair of tubular segments 14 which are disposed between the lower end of the wheel 11 and the flange *b*, the segments being provided between their ends with flanges *d* which are suitably secured to the lower side of the lid 10.

The parts thus described are of simple construction and may be conveniently assembled, and if a reciprocatory rotary motion is imparted to the gear wheel 11, the 70 shaft and dolly will have a corresponding movement for agitating the contents of the tub, the shaft 12, on account of its bearings being normally maintained in a vertical position, and being adapted to have 80 slidable movements in said bearings, so that if desired by an operator, the dolly may suitably engage the fabrics *x* (Fig. 1.), this being of advantage since the contents of the tub, as to volume, may not be uniform at all 85 times.

The wheel 11 is actuated by means of a rack-bar 15 movable by the hand-lever 16, the latter having a pivotal connection therewith, as indicated at 17. The hand-lever 16 90 is mounted pivotally between its ends, as indicated at 18, upon a bracket 19 which is suitably secured to the side of the tub.

Numeral 20 indicates a hanger which is 95 secured to the bottom of the tub. Its lower end has a wrist-pin *e* mounted therein to provide bearings for a toothed gear 21, the latter being provided with a pivot-pin 22 upon which is mounted an actuating-rod 23, the opposite end of said rod having a pivotal 100 connection, as indicated at 24, upon the lower end of the lever 16; and as thus described, since the toothed gear 21 will be rotated during operation and will perform the functions of a balance wheel, it is a material 105 advantage as an aid in operating the hand-lever, while effecting reciprocatory rotation of the shaft 10, for agitating the contents of the tub.

In instances when the tub is nearly filled 110 with water, together with the clothing or other fabrics to be washed, a greater mo-

mentum is required, and therefore a combined vehicle and impulse-member 25 is provided, consisting of a pair of wheels 26 rigidly mounted on an axle 27, the latter having a pinion 28 mounted thereon.

Numerals 29 indicate a pair of links having pivotal mountings 30, for their upper ends, preferably, upon the legs 9, each link at its inner end being provided with a collar 31, and it will be understood that the pair of collars 31 provide bearings for the ends of the axle 27.

Any suitable means may be provided for moving the pinion 28 into engagement with the rotatable toothed gear 21 so that the wheels 26 may provide additional momentum, said means also being operative for moving the axle downwardly so that the wheels may support the weight of the tub, 15 the means herein shown consisting, in part, of the pair of rearwardly extending, segmental arms 32 with which the links are provided and which extend rearwardly from the collars 31, each arm being disposed in one 20 of the guides or apertured brackets 33 which is secured upon a leg 9, below the pivotal mounting 30 of a link 29, and it will be understood that the axle 27 and its wheels 26 may have a swinging movement in one direction to cause the teeth of the pinion 28 to engage the toothed gear 21, whereby the greater degree of momentum will be provided for actuating the shaft 12.

Numerical 34 indicates a foot-rail which 35 connects the outer ends of the arms 32, and in order that the pinion 28 may be maintained in engagement with the toothed gear 21 each arm 32 is provided with a notch 35 for receiving the lower end of a pawl-rod 40 36, said rods 36 being provided with springs 37 tending to normally press them in a direction of the arms 32, the upper ends of the pawl-rods, as best shown in Figs. 1 and 5, being pivotally connected with the handles 45 38 which are pivotally mounted at their inner ends as indicated at 39, whereby the rods 36 may be moved upwardly, against the force of the springs 37, the links 29 and wheels 26 thereupon having a downward 50 swing movement by action of gravity, the arms 32 moving in an arc of a circle, the center of which is a pivotal mounting 30 of a link 29. An operator, by a downward pressure on the foot-rail 34 may cause engagement 55 of the teeth of the pinion 28 with the toothed gear 21, and the parts mentioned are arranged for convenient operation.

The arms 32 are each provided with a second notch 40, and the actuating-rod 23, at its 60 outer end, is provided with a handle 41, and the machine may be readily elevated from the floor with its weight supported by the wheels, the operator, for this purpose using the hand-lever 16 or handle 41 for elevating 65 the rear side of the tub to permit the wheels

26 to swing downwardly to the position shown in Fig. 3, the pawls, by use of handles 38, being first released from the notches 35 to permit this movement.

When the links 29 are disposed in substantially a vertical position, the pawls will engage in the notches 40, which operates to maintain the links in fixed relation with the longitudinal axis of the tub, and the machine may then be moved about a room, member 75 25 operating as a vehicle for this purpose, this feature obviously being a great advantage.

Numerical 42 indicates a guide provided for the top of the lid which, during operation, 80 maintains the rack-bar in engagement with the gear wheel 11. The rack-bar, therefore, may be swung to the position shown in Fig. 3, if desired, when using the lever 16 or handle 41 for moving the machine; and for actuating 85 the shaft 12, the rack-bar may be swung forwardly to be disposed as shown in Fig. 2.

When only a limited degree of momentum is required for actuation of the shaft 12, the 90 pawls may be disengaged from the notches and the wheels and legs 9 will rest upon the floor, and since the pinion 28 will be disengaged from the toothed gear 21, the latter, during operation, will rotate as a balance 95 wheel.

By referring to Fig. 1 it will be seen that the toothed gear 21 is disposed in line with the longitudinal axis of the tub, and therefore in line with the center of gravity, 100 which is obviously an advantage, also that the axle and wheels 26 are disposed in the same line when the links 29 have been swung inwardly for engagement of the pinion 28 with the toothed gear 21.

What I claim as my invention is,—

1. In devices for the purposes described, a tub having leg supports and provided with agitating devices including a dasher-shaft having a gear wheel and also including a 110 rack-bar adapted to engage the gear-wheel, a toothed gear in bearings below the bottom and carried by the tub, a pair of pivotally mounted links below the tub each being provided with a segmental arm, an axle having 115 bearings in the pair of links and having wheels rigidly mounted thereon, a pinion rigidly mounted on the axle, a foot-rail connecting the segmental arms and movable for moving the pinion of said axle into engagement with the toothed gear, an actuating-rod connected with the toothed gear, a hand-lever pivotally mounted between its ends and connected with the rack-bar and actuating-rod, and being movable for causing co-incident actuation of the wheels of said axle and the gear wheel of the dasher-shaft.

2. In combination with a tub having its bottom provided with a hanger and having leg-supports, apertured brackets on the leg- 120

supports, a dasher-shaft provided with a gear-wheel and disposed in line with the axis of the tub, a rack-bar adapted to engage the gear-wheel, a toothed gear having bearings in the hanger, an actuating-rod pivotally connected with the toothed gear, a pair of pivotally mounted links below the tub each having a segmental arm engaging in an apertured bracket, an axle having bearings in the pair of links and having wheels non-revolubly mounted thereon, a pinion mounted non-revolubly on the axle, said links being adapted to have a swinging movement for moving the pinion of the axle 10 into engagement with the toothed gear, a hand-lever connected with the rack-bar and actuating-rod and adapted to have swinging movements for causing coincident actuation of the wheels of said axle and the gear-wheel of said dasher-shaft.

3. In devices for the purpose described, a tub having leg-supports and provided with agitating devices including a dasher-shaft having a gear-wheel and including a rack-bar engaging the gear-wheel, a toothed gear in bearings below the tub, a pair of pivotally mounted links below the tub, an axle having bearings in the links and having wheels rigidly mounted thereon, a pinion 25 rigidly mounted on the axle, said links being movable for moving the pinion of the axle into engagement with the toothed gear, means to maintain the pinion of the axle in engagement with said toothed gear, an actuating-rod connected with the toothed gear, and movable means connected with the rack-bar and actuating-rod for causing actuation of the wheels of the axle and said gear-wheel.

4. In combination with a wash tub having supporting-members and provided with agitating devices including a vertical shaft provided with a gear wheel, a rack-bar en-

gaging the gear-wheel, apertured brackets on said supporting-members, a toothed gear 45 having journaled bearings below and supported by the tub, an actuating-rod connected with the toothed gear, a pair of links each having a pivotal mounting for its upper end upon said supporting-members and 50 provided with a curved arm having a longitudinal part disposed equi-distant from said pivotal mounting and engaging in an apertured bracket, an axle journaled in and near the inner ends of said links and having 55 wheels non-revolubly mounted thereon, a pinion mounted non-revolubly on the axle, said links being movable in a circle's arc for disposing the pinion of the axle in engagement with said toothed gear, a pawl-rod for 60 engaging the curved arm of a link for maintaining said pinion in engagement with said toothed gear, and movable means for causing simultaneous actuation of the rack-bar and said actuating-rod.

5. In combination with a washing machine consisting of a tub provided with legs and agitating devices and having a rock-lever movable for actuating said agitating devices, a toothed gear below the tub revolvable by the rock-lever, a pair of links below the tub, an axle journaled in the links and provided with wheels, a pinion on the axle, said links being adapted to have swinging movements in one direction to dispose the 70 wheels below the plane of the legs, and adapted to have swinging movements in an opposite direction to cause engagement of the pinion of said axle with the toothed gear.

In testimony whereof, I have affixed my signature in presence of two witnesses.

FRANKLIN B. BECKWITH.
